Terry Madden.

UNITED STATES PATENT OFFICE.

ANTOINE SOUDY, OF LYON, FRANCE.

LUBRICATING-CUP.

Specification of Letters Patent. Patented Sept. 14, 1920.

1,352,847.

Application filed April 7, 1919. Serial No. 288,153.

To all whom it may concern:

Be it known that I, ANTOINE SOUDY, of Lyon, France, a citizen of the French Republic, have invented certain new and useful Improvements in Lubricating-Cups, of which the following is a specification.

This invention relates to improvements in lubricating cups.

The characteristic feature of the cup is that the lid or cap is a portion of hollow sphere larger than a hemisphere and forms a very air-tight closing by the close fit of its outer face against a spherical inner surface forming the upper part of the chamber in the body of the lubricator. The lower edge of the cap is serrated and the said cap can be rocked in any direction in order to expose one or other of the openings formed by the serrations in its edge and through which is introduced the nozzle of the oil can for filling the lubricator. The cap is restored to its medial position by means of a laterally flexible spring which is so arranged that one of its ends is axially secured internally to the lubricator and the other end is similarly axially secured to the interior of the cap in such manner that the spring constantly tends to restore the cap to its normal position and tends to keep it in said position in order to insure a dust-tight closure.

The annexed drawing shows an example of construction of the invention.

Figure 1 is a vertical section of the oil cup, the cap of which is closed.

Fig. 2 is a plan view of Fig. 1.

Fig. 3 is a similar section, the cap being open and.

Fig. 4 is an elevation of the lubricator arranged horizontally, the cap being open.

The lubricator is composed of a body *a* having a cylindrical outer surface comprising a hexagonal surface either at *b* or at *c*, as shown in Fig. 4, this hexagonal surface serving for putting in place or removing the lubricator. The inside of the body *a* is conic at its base and spherical at its top at *d*.

The cap or lid *e* is a portion of a hollow sphere larger than a hemisphere on the edge of which are provided semi-circular and equidistant notches *h*. It is provided with a button *g* projecting externally and prolonged inside the sphere by a pin of which the length is so determined that it does not reach the central point of the sphere.

A spiral spring *f*, of which the outer diameter is slightly greater than that of the cylindrical central passage forming an extension of the inner conical surface of the body *a*, is forcibly helved by one of its ends 60 into the said passage in order to be secured in the body *a* and lie in the central part of the cavity of the latter while still leaving sufficient passage for the oil introduced into the lubricator. The other end of said 65 spring engages on the pin of the button *g* and is thus attached to the cap *e*, as shown in Figs. 1 and 2.

The length of said spring is so calculated that it is slightly compressed when the cap 70 *e* is placed in the body *a* so that the edge of the cap presses against the spherical part *d*. In mounting the parts, the edge *s* of the part *b* of the body *a* is afterward turned in against the outer surface of the sphere, 75 while still leaving the necessary play for allowing the rotation of said sphere in its socket, from which it can no longer be removed after the aforesaid edge has been turned inward.

The slight compression of the spring *f* is sufficient to constantly push the cap against the edge of the socket *d* without preventing the free rotation of said cap by the operator's fingers which grasp the button *g* 85 on the surface of the cap.

This cap can be rotated horizontally on its own axis as the spring is not secured to the pin of the button *g* and it can also be tilted in all directions while bending the 90 spring *f* as shown in Fig. 3. Owing to said simultaneous or successive rotation and tilting of the lid there is obtained without trouble a lubricating hole whatever the position of the body *a*, as one or other of the 95 notches *h* is brought forward and through which the oil can be introduced into the lubricator by passing through said orifice.

The oil cup can be arranged horizontally as represented in Fig. 4 or in any inclined 100 position between the horizontal and the vertical.

When the cap has been tilted and then released it immediately returns to its normal position (Fig. 1) under the action of the 105 spring *f*. The closure is therefore automatic and dust-tight, and there is no fear of leakage of oil when the lubricator is in an inclined or horizontal position.

The lubricator cup can be constructed in 110

any size, from the usual minimum to the largest type. The body *a* together with the inner chamber can have any suitable shape.

This same lid device can be employed as 5 closing means for reservoirs or chambers other than lubricating cups.

What I claim as my invention and desire to secure by Letters Patent of the United States is:—

- 10 1. A cup comprising a body having a bore and a chamber having an internally spherical mouth in continuation of said bore, a hollow cap in the form of a portion of a sphere larger than a hemisphere fitting in said mouth and a lateral spring one end of which is axially fixed in said body and the other end axially fixed in said cap and allowing said cap to be tilted to allow oil to be introduced into said chamber, the said 15 spring automatically retarding said cap when released to the closed position.
- 15 2. A lubricating cup comprising a body having a bore and a chamber having an internally spherical mouth in continuation of said bore, a hollow cap in the form of a portion of a sphere larger than a hemisphere fitting in said mouth and a lateral spring one end of which is axially fixed in said body and the other end axially fixed in said cap and allowing said cap to be tilted to allow oil to be introduced into said chamber, the said 20 spring automatically retarding said cap when released to the closed position.

2. A lubricating cup comprising a body having a bore and a chamber having an internally spherical mouth in continuation of said bore, a hollow cap in the form of a portion of a sphere larger than a hemisphere fitting in said mouth and a lateral spring one end of which is axially fixed in said body and the other end axially fixed in said cap and allowing said cap to be tilted to allow oil to be introduced into said chamber, the said 25 spring automatically retarding said cap when released to the closed position.
2. A lubricating cup comprising a body having a bore and a chamber having an internally spherical mouth in continuation of said bore, a hollow cap in the form of a portion of a sphere larger than a hemisphere fitting in said mouth, a knob on the exterior of said cap, a pin forming an extension of said knob extending into said cap, and a laterally flexible helical spring, the 30 one end of which surrounds said pin and is axially held thereby, and the other end fits tightly into said bore and is axially held thereby.

In witness whereof I have signed this 35 specification in the presence of two witnesses.

ANTOINE SOUDY.
